(57) **CLAIM**

I claim, the ornamental design for an appliance for hair removal, as shown and described.

DESCRIPTION

FIG. 1 is a side elevation view of an appliance for hair removal, showing my new design;

FIG. 2 is an opposite side elevation view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a top perspective view thereof; and,

FIG. 8 is a bottom perspective view thereof.

The broken lines shown in the drawings illustrate portions of the article and form no part of the claimed design.
